UNITED STATES PATENT OFFICE.

THOMAS GEORGE OWENS THURSTON, OF WESTMINSTER, LONDON, ENGLAND, ASSIGNEE
TO VICKERS LIMITED, OF LONDON, ENGLAND.

WARSHIP AND OTHER SEA-GOING VESSEL.

1,246,494.

Specification of Letters Patent. Patented Nov. 13, 1917.

Application filed March 30, 1916. Serial No. 87,843.

To all whom it may concern:

Be it known that I, THOMAS GEORGE OWENS THURSTON, a subject of the King of Great Britain, residing at Vickers House, 5 Broadway, Westminster, in the county of London, England, have invented certain new and useful Improvements in or Relating to Warships and other Sea-going Vessels, of which the following is a specification.

The invention relates to ships, particularly large surface-vessels employed in naval warfare of the kind in which chambers are provided around the ship for the purpose 15 of protecting it from the effect of submarine explosions by serving as resistance and expansion chambers for the explosion gases.

According to this invention the chambers are situated along the sides of the ship for 20 a suitable distance forward and aft of midships, and are so constructed that the explosion gases of the torpedo or mine are allowed to expand into a voluminous outer compartment, the outer wall of which is 25 convex or is similarly formed with a pronounced projecting wall in contact with the sea, and finally to be safely resisted by the strong structural form of an inner compartment of the said chambers. The inner wall 30 or back of the outer compartment constitutes a partition between the outer and inner compartments and is composed of a suitably stiffened bulkhead or inner framing, which may be additionally stiffened to 35 resist breakage by a longitudinal girder or girders extending along its back and preferably composed of semi-circular or box shaped plating and also preferably supported by means of flexible cables or the 40 like extending transversely across the said girder and connected at their ends to the upper and lower portions of the bulkhead or to other suitable parts.

The inner compartment which provides 45 the final and strongest resistance to the explosion gases, is formed with a strong plated bulkhead which is preferably made approximately semi-circular in shape, that is to say it extends inwardly from the upper portion and then extends outwardly toward the lower portion of the outer compartment.

In order that the said invention may be clearly understood and readily carried into effect we will describe the same more fully

with reference to the accompanying drawings, in which:—

Figures 1 and 2 are respectively a transverse section and a diagrammatic plan showing one side of a ship provided with a constructional form of the aforesaid chamber. 60

Figs. 3 and 4 are views similar to Figs. 1 and 2 showing a modified form of the chamber, and

Fig. 5 is a view similar to Figs. 1 and 3 showing another modified form of the chamber. 65

A represents the aforesaid voluminous outer compartment whose outer wall A' projects beyond the contour of the ship and whose inner wall or back A² constitutes 70 the aforesaid partition between the outer and inner compartments. B represents the said inner compartment whose outer wall is constituted by the said inner wall or back A² of the outer compartment and whose 75 inner wall is constituted by the bulkhead B' of approximately semi-circular formation. A³ (Fig. 1) represents the aforesaid girder carried by the inner wall or back A² and A⁴ represents one of the supporting 80 cables of this girder.

Referring more particularly to Figs. 1 and 2 the outer compartment A is made as voluminous as possible by extending the outer projecting or convex wall A' a suitable distance from the bulkhead or inner framing constituting the inner wall or back A² which performs the duty of providing a longitudinal member of the structural portion of the main ship's hull as well as to 85 support the weight of the side armor A⁵ and other parts located above it. The said outer compartment is constructed of a braced framing or of considerably lightened plate frames arranged to combine the bulkhead or inner framing A² and the outer wall A' of the compartment in the manner of an integral structural girder adapted to resist the water pressure on the said outer wall. 90

The outer wall, when the distance separating it from the bulkhead or inner framing A² is moderate, is preferably composed of a simple frame of rolled section, but where this distance is large the outer wall may be formed and constructed in the manner of 100 a double hull framed in the cellular manner as is customary in the ordinary construction of a ship's side framing and plating. In 105

either case the aforesaid braced open framing or considerably lightened plate frames are utilized in the interior of the outer compartment to allow of the diffusion of the 5 explosion gases and consequent reduction of the pressure before entering (if they possess sufficient energy) the strong inner compartment B situated immediately behind the bulkhead or inner framing A² of the outer 10 compartment.

The curved bulkhead B' of the inner compartment B is constructed in a manner which will enable it to resist a large pressure by reason of its form and its framing is constructed as independently as possible from 15 that of the outer compartment A in order that any damage occurring to the latter may not be communicated directly to the rear of the curved bulkhead B' which constitutes 20 the final resistance. The said bulkhead B' may however be constructed as a vertically framed bulkhead, in which case the curvature (which is the factor giving a high resistance to pressure) is made in a corrugated 25 form in plan view between the successive vertical frames behind the bulkhead.

In the constructional forms of the invention shown by Figs. 3 and 4 and by Fig. 5, the bulkhead or inner framing A² is constituted by a plate of relatively light character; this plate may if desired be perforated. In these constructions the girder A³ is dispensed with. The outer compartment A is also not provided with the braced open 35 framing shown in Fig. 1.

The outer and inner compartments which extend as far as practicable through the length of the vital portion of the ship may be divided into a number of independent 40 sub-compartments by means of transverse bulkheads or partitions a, b (see Figs. 2 and 4). The transverse bulkheads a, a in the outer compartment A are spaced at a convenient distance apart, and the partition of 45 the inner compartment is arranged in a similar manner except that the transverse bulkheads b, b may as shown by Fig. 2 be situated successively forward and abaft the transverse bulkheads a, a, which sub-divide 50 the outer compartment. In this manner, the separate transverse bulkheads of the compartments are stepped or staggered so that the damage occurring from an explosion can be more satisfactorily localized. The bulkheads a, a and b, b may be arranged to form 55 relatively small changes a', a' and b', b' for the reception of oil fuel.

Toward the bow of the ship, the projecting outer compartment may be gradually 60 merged into the form of the ship's lines forward, or may be continued to some distance ahead of the ordinary stem. At the after end, adjacent to the propeller shafting, the said outer compartment may either be gradually 65 merged into the ordinary form of the

run of the vessel, or it may be constructed at its after extremity in the form of a projecting shield incorporated with the vessel's hull in a manner suitable to give the form necessary for protecting the shafting and 70 propellers.

When any of the outer compartments have become damaged by the entry of explosion gases, which have finally been resisted by the strong form of the inner compartment, it 75 may be desirable to correct the heel of the ship by admitting water to flood certain inner compartments situated on the opposite side of the ship. This can be done automatically by connecting the compartments 80 by means of an open pipe leading to any suitable water-tight compartments on the other side of the center line of the ship, or by other suitable means. Also compressed air may be used to discharge a portion of the 85 water, from any flooded compartments, so that the ship can be made to float without taking up any undesirable angle of heel after any portion of the ship's side has suffered through an explosion.

What I claim and desire to secure by Letters Patent of the United States is:—

1. A vessel having along its side a series of chambers for the purpose of protecting it from the effect of submarine explosions by 95 serving as resistance and expansion chambers for the explosion gases, each of the said chambers, comprising a voluminous outer compartment having an outer wall which projects beyond the usual and normal contour of the vessel, and an inner compartment of strong structural form.

2. A vessel having along its sides a series of chambers for the purpose of protecting it from the effect of submarine explosions 105 by serving as resistance and expansion chambers for the explosion gases, each of said chambers comprising a voluminous outer compartment, an outer wall for said outer compartment which projects beyond the normal contour of the vessel, an inner compartment of strong structural form, and an inner wall for said outer compartment which constitutes a partition between the said outer and the said inner compartments.

3. A vessel having along its sides a series of chambers for the purpose of protecting it from the effect of submarine explosions by 115 serving as resistance and expansion chambers for the explosion gases, each of said chambers comprising a voluminous outer compartment, an inner compartment of strong structural form, an outer wall for the said outer compartment which projects beyond the normal contour of the vessel, an inner wall for the said outer compartment which constitutes a partition between the said outer and the said inner compartments, and means for stiffening said partition.

4. A vessel having along its sides a series 130

- of chambers for the purpose of protecting it from the effect of submarine explosions by serving as resistance and expansion chambers for the explosion gases, each of said 5 chambers comprising a voluminous outer compartment, an inner compartment of strong structural form, an outer wall for the said outer compartment which projects beyond the normal contour of the vessel, an 10 inner wall for the said outer compartment which constitutes a partition between the said outer and the said inner compartments, and longitudinal girders for stiffening said partition.
- 15 5. A vessel having along its sides a series of chambers for the purpose of protecting it from the effect of submarine explosions by serving as resistance and expansion chambers for the explosion gases each of said 20 chambers comprising a voluminous outer compartment, an inner compartment of strong structural form, an outer wall for the said outer compartment which projects beyond the normal contour of the vessel, an 25 inner wall for the said outer compartment which constitutes a partition between the said outer and the said inner compartments and longitudinal girders for stiffening said partition, said longitudinal girders being 30 supported by means of flexible cables extending transversely across the girders and secured at their ends.
6. A vessel having along its sides a series 35 of chambers for the purpose of protecting it from the effect of submarine explosions by serving as resistance and expansion chambers for the explosion gases, each of the said chambers comprising a voluminous outer compartment having an outer wall which 40 projects beyond the usual and normal contour of the vessel, and an inner compartment of strong structural form, said outer and inner compartments being divided into sub-compartments by transverse bulkheads.
- 45 7. A vessel having along its sides a series of chambers for the purpose of protecting it from the effect of submarine explosions by serving as resistance and expansion chambers for the explosion gases, each of said 50 chambers comprising a voluminous outer compartment, an outer wall for said outer compartment which projects beyond the normal contour of the vessel, an inner compartment of strong structural form, and an 55 inner wall for said outer compartment which constitutes a partition between the said outer and the said inner compartments, said outer and inner compartments being
- divided into sub-compartments by transverse bulkheads.
8. A vessel having along its sides a series of chambers for the purpose of protecting it from the effect of submarine explosions by serving as resistance and expansion chambers for the explosion gases each of 60 65 said chambers comprising a voluminous outer compartment, an inner compartment of strong structural form, an outer wall for the said outer compartment which projects beyond the normal contour of the vessel, an 70 inner wall for the said outer compartment which constitutes a partition between the said outer and the said inner compartments, and longitudinal girders for stiffening said partition, said outer and inner compartments being divided into sub-compartments by transverse bulkheads.
9. A vessel having along its sides a series of chambers for the purpose of protecting it from the effect of submarine explosions by 75 80 serving as resistance and expansion chambers for the explosion gases, each of said chambers comprising a voluminous outer compartment, an inner compartment of strong structural form, an outer wall for 85 the said outer compartment which projects beyond the normal contour of the vessel, an inner wall for the said outer compartment which constitutes a partition between the said outer and the said inner compartments, and longitudinal girders for stiffening said 90 partition, said longitudinal girders being supported by means of flexible cables extending transversely across the girders and secured at their ends, said outer and inner 95 compartments being divided into sub-compartments by transverse bulkheads.
10. A vessel having along its sides a series of chambers for the purpose of protecting it from the effect of submarine explosions 100 by serving as resistance and expansion chambers for the explosion gases, each of said chambers comprising a voluminous outer compartment, an outer wall for said outer compartment which projects beyond the normal contour of the vessel, an inner compartment constituted by a strong plated approximately semi-circular shaped bulkhead, which extends inwardly from the upper portion and then extends outwardly toward 105 the lower portion of the outer compartment, and an inner wall for said outer compartment which constitutes a partition between said outer and inner compartments.

In testimony whereof, I affix my signature. 115
THOMAS GEORGE OWENS THURSTON.

It is hereby certified that in Letters Patent No. 1,246,494, granted November 13, 1917, upon the application of Thomas George Owens Thurston, of Westminster, London, England, for an improvement in "Warships and other Sea-Going Vessels," an error appears in the printed specification requiring correction as follows: Page 2, line 56, for the word "changes" read *chambers*; and that the said Letters Patent should be read with this correction therein that the same may conform to the record of the case in the Patent Office.

Signed and sealed this 12th day of February, A. D., 1918.

[SEAL.]

J. T. NEWTON,

Commissioner of Patents.
